UNITED STATES PATENT OFFICE

129,838

DESIGN FOR A RAILROAD CROSSING SIGNAL

Samuel E. McFarland, Los Angeles, Calif.

Application April 2, 1941, Serial No. 100,102

Term of patent 7 years

To all whom it may concern:

Be it known that I, Samuel E. McFarland, a citizen of the United States, residing in the county of Los Angeles and State of California, have invented a new, original, and ornamental Design for a Railroad Crossing Signal, of which the following is a specification, reference being had to the accompanying drawing, forming part hereof.

Fig. 1 is a side elevational view of a railroad crossing signal showing my new design; and Fig. 2 is a front elevational view thereof.

The dominant features of my design reside in the portions shown in full lines in the drawing.

I claim:

The ornamental design for a railroad crossing signal, as shown and described.

SAMUEL E. McFARLAND.
